UNITED STATES PATENT OFFICE.

DANIEL B. McALLISTER, OF SOUTH BOSTON, MASSACHUSETTS.

TOBACCO-PIPE.

SPECIFICATION forming part of Letters Patent No. 739,101, dated September 15, 1903.

Application filed September 11, 1902. Serial No. 122,924. (No model.)

To all whom it may concern:

Be it known that I, DANIEL B. McALLISTER, a citizen of the United States, residing at South Boston, in the county of Suffolk and State of Massachusetts, have invented certain new and useful Improvements in Tobacco-Pipes; and I do hereby declare the following to be a full, clear, and exact description of the invention, such as will enable others skilled in the art to which it appertains to make and use the same.

This invention relates to tobacco-pipes; and it consists in the novel construction and combination of the parts hereinafter fully described and claimed.

In the drawings, Figure 1 is a side view of the bowl of the pipe, partly in section. Fig. 2 is a plan view of the same.

A is the bowl of a tobacco-pipe of any approved make.

B is a screw-threaded metal ring secured around the outside of the rim of the bowl.

C is a hollow cap or cover which is screwed onto the ring B after the pipe has been filled with tobacco and lighted.

D is a downwardly-projecting spring-chamber suspended from the center portion of the top of the cap C.

E is a perforated extinguishing-plate provided with a stem e, which slides vertically in the chamber D, and d is a spring arranged in the said chamber around the stem e. F is a button of non-heat-conducting material secured to the top of the stem e. The spring is arranged between the bottom c of the said

chamber and the button F, and it normally holds the perforated plate E in a raised position clear of the tobacco in the pipe.

The cap C is provided with holes f for the passage of air. The cap protects the burning tobacco from the effects of the wind, and the burning tobacco may be pressed gently from time to time to make it burn evenly. The burning tobacco may be extinguished by pressing the perforated plate down firmly for a few seconds without drawing air through the pipe.

What I claim is—

The combination, with the bowl of a tobacco-pipe, and an externally-screw-threaded ring secured around its rim; of a removable perforated cap screwing on the said ring and provided with a chamber depending from its upper portion, an extinguishing-plate provided with a stem slidable in the said chamber, a finger-button at the upper end of the said stem, and a spring arranged in the said chamber between the bottom thereof and the said button and normally supporting the said extinguishing-plate, the top of the said cap operating as a stop for the said button to strike against when depressed, substantially as set forth.

In testimony whereof I affix my signature in presence of two witnesses.

DANIEL B. McALLISTER.
